REFRIGERANT COMPRESSOR

Lawrence C. Smith, Kenmore, N. Y., assignor to
Fedders Manufacturing Company, Inc., Buffalo, N. Y.

Application May 10, 1933, Serial No. 670,313

4 Claims. (Cl. 230—172)

This invention relates to improvements in valve and oil separating devices for refrigerant compressors.

In refrigeration systems, volumes of the lubricating oil for the working parts of the compressor are unavoidably introduced into the refrigerant circuit, and these volumes must be removed constantly to retain the full efficiency of the system. In the present invention, an oil separating and return device is directly associated with the compressor in a compact structure including a novel valve plate arrangement wherein it will be found that the entire device is constructed in a manner calculated to simplify a compressor structure by elimination of parts and ease of accessibility as more fully pointed out in the accompanying specification and drawings, wherein:

Fig. 1 is a side elevation of a compressor having the devices of the present invention incorporated therein;

Fig. 2 is a section on the line 2—2 of Fig. 1, portions of the cylinder block and head being broken away to show the valve and oil return arrangement;

Fig. 3 is a section on the line 3—3 of Fig. 2; and Fig. 4 is a section on the line 4—4 of Fig. 2.

For exemplary purposes, the present invention is shown applied to a single cylinder refrigerant compressor having a cylinder block 10 and a crankcase 11 formed as an integral unit. The cylinder block is bored to receive a piston 12 which is reciprocated by an eccentric and strap unit 13, the eccentric thereof being secured to a driven shaft 14 which is mounted in suitable bearings in the crankcase 11. The crank shaft 14 may also carry a counterweight 15 to balance the weight of the piston during operation.

The cylinder block 10 is provided with a head, comprising a head casting 17 and a valve plate 18, both of which are secured to the cylinder block 10 by the bolts 19 which extend therethrough. The head casting 17 is formed with an input chamber 21 leading to a fitting 22, having a connection with the output side of an evaporator 45 or the like (not shown). An output chamber 23 is also formed in the head casting, and it communicates with a refrigerant condenser or the like through an output fitting 24.

The valve plate 18 is provided with an output valve 26 which comprises a flexible strip 27 mounted within the chamber 23 by spaced studs 28 (Fig. 2) and adapted to seat on a valve seat 30 formed in the plate 18. The movement of the valve strip 27 is limited by a bent stop member 31, which in itself is releasable when the load of

springs 32 is overcome by the compressive force of the piston 12. The input valve 35 comprises a flat strip of flexible metal bifurcated as indicated by the numeral 36 to clear the input port 37. The extremities of the bifurcations contain holes 38 for receiving dowels 39 whereby the valve is retained in position over an input port 41 formed in the valve plate 18.

It is proposed to separate the oil from the gaseous refrigerant volumes directly in the input chamber 21, and baffle members 42 and 43 are positioned therein to divert the incoming gas volumes so that oil will be impinged upon them and on the walls of the chamber 21 before introduction of the separated gas into the bore of the compressor chamber. The baffle member 42 is formed as a depending rib member of the casting 17, while the member 43 comprises a pipe mounted in the input port of the plate 18. This pipe protects the input port 41 from oil volumes 20 which may be deposited gravitationally on the bottom wall of the chamber 21.

Oil is directed from the chamber 21 to the crankcase 11 through a drilled passage 44 in the valve plate 17 and a communicating vertical passage 45 drilled in the cylinder block 10. The lower extremity of the passage 45 is reduced in diameter as indicated by the numeral 46 so that only a small orifice is open to the crankcase 11. It has been found advisable to provide baffles or the like in the passage 45 to protect the chamber 21 from liquid surges occasioned by pulse or back pressure effects in the crankcase 11 as a result of the rotation of the eccentric and counterweight members. A convenient method of forming a baffle in the passage 45 is by inserting a twisted length of metallic ribbon 47 therein, whereby the helices 48 thereof are adapted to be engaged by oil which is thrown back from the crankcase 11.

It will be observed that both valves and the oil protective device 43 are mounted on the valve plate 18, and that a simple disassembly operation is all that is required to provide access to these essential portions of the compressor for replacement or repair. It will also be noted that portions of the cylinder block and valve plate 18 may conveniently be utilized to contain the oil recovery passages, thus eliminating the use of extra conduits, joints and the like.

It will be appreciated that the invention is applicable to numerous types of compressors and, therefore, it is not intended that its use be specifically limited to the type herein shown except 55

as pursuant to the accompanying claims, where-
in I claim:

1. In a refrigerant compressor the combina-
tion of a cylinder block, a crankcase, a head for
the cylinder block formed with input and output
ports, a valve on each port, an input chamber
formed in the head and communicating with
said input port, an oil passage formed in the
block and connecting the input chamber to the
10 crankcase, and a baffle in the input chamber dis-
posed about the input port to prevent oil entry
therein.

2. A refrigerant compressor comprising a cylin-
der block, and a crankcase, a head for the block
15 comprising a head member having input and out-
put chambers and a valve plate interposed be-
tween the block and member, said plate having
input and output ports connecting the block to
said input and output passages respectively, an
20 output valve for the output port mounted on said
plate within the output chamber, an input valve
for the input port mounted on the plate and open-
ing within the block, an oil passage in the block
connecting the input chamber to the crankcase, a
25 baffle member mounted on said plate about the
input port in the input chamber to prevent oil
entry therein, and an insert member in said pas-

sage forming a tortuous oil path therein to pro-
tect the input chamber from oil surges from the
crankcase.

3. In a refrigerant compressor the combination
of a cylinder block, a crankcase, a head for the
cylinder block formed with input and output
ports, a valve on each port, an input chamber
formed in the head and communicating with said
input port, baffle means in the input chamber
for gravitationally separating oil from the re-
frigerant gas, an oil passage formed in the block
and connecting the input chamber to the crank-
case, and an insert member in the passage of the
block formed to provide a tortuous oil path there-
in to protect the input chamber from oil surges
15 from the crankcase.

4. A refrigerant compressor comprising a cyl-
inder block and a crankcase, a head for the block
having input and output chambers formed with
input and output ports respectively, a valve on
each port, a baffle member disposed about the in-
put port in the input chamber and terminating
in spaced relation to the upper wall of said chamber,
and an oil return passage connecting the in-
put chamber to the crankcase.
